UNITED STATES PATENT OFFICE.

JOSEPH P. PAULISSEN, OF KANKAKEE, ILLINOIS.

REINFORCED-CONCRETE BUILDING.

1,388,752.

Specification of Letters Patent. Patented Aug. 23, 1921.

Application filed January 24, 1921. Serial No. 439,443.

To all whom it may concern:

Be it known that I, JOSEPH P. PAULISSEN, a citizen of the United States, and a resident of Kankakee, in the county of Kankakee, and the State of Illinois, have invented certain new and useful Improvements in Reinforced-Concrete Buildings, of which the following is a specification.

This invention relates to a building structure of reinforced concrete and is especially adapted, in the form shown for fireproof building designed for use as stores, warehouses, or apartments, or the ideas embodied in the structure shown and described may 10 be employed in connection with buildings of different sizes and used for a great variety of purposes. I do not therefore wish to be limited to a building designed for any particular purpose, or of any special size or 15 20 design, as the outward appearance of the building and its interior arrangement may be varied to suit the builder or owner.

My invention consists in the novel features of construction hereinafter described, 25 pointed out in the claims and shown in the accompanying drawings, in which:—

Figure 1 is a partial side elevation, the side wall and the rear wall portion of the building being broken away.

30 Fig. 2 is a section on the line 2—2 of Fig. 1.

Fig. 3 is a plan view of a corner portion of the roof, the top covering being removed.

Fig. 4 is a longitudinal section through a 35 portion of the roof.

Fig. 5 is a detail section through a cornice.

Fig. 6 is a floor section, showing the joint formed between two sections of the floor.

Fig. 7 is a section transversely through a 40 supporting beam and through a portion of the floor, at right angles to the section shown in Fig. 6.

Fig. 8 is a detail view partly in section showing the method of reinforcing certain 45 floor supporting beams and securing them to supporting upright columns.

Fig. 9 is a cross section through a beam showing the arrangement of the reinforcing elements.

50 Fig. 10 is a detail section of a portion of an upright showing a wear plate for a bolt-head, or nut.

Fig. 11 is a plan view showing the method of tying top beams at their meeting ends.

55 In the construction shown in the drawings I employ concrete piers 1 capped by a metal

cap 1^a and in these caps fit the lower ends of the upright posts of the lower floor. These comprise the corner posts 2, front posts 3 and side posts 4. Extending lengthwise of 60 the building are concrete beams 5, formed adjacent their ends with arches 6, the ends resting on the posts 2 and 4, the ends of the beams meeting on the posts 4, the flanges 6 bearing against the posts on which the beams 65 rest. It will be noted that the posts 2 and 4 are duplicated for floors above the first, while the posts 3 on upper floors are replaced by posts 3^a with reduced lower end portions.

The beams 5 support joists 7 on which rest 70 floor slabs, also of reinforced concrete, 8, having joints as at 9. At the sides adjacent the front a beam 10 is employed between the uppermost corner post 2 and the post 4^a this beam sloping rearwardly to conform to the 75 inclination of the roof. To the rear of this point the various posts 4^a are connected by a tie rod 11. Between the various upright posts shown is placed a filling of brick, as at 16, stone or tile, with such doors and windows as may be required.

Extending cross wise of the building and resting on the beam 5 are beams 13 having arched flanges 14 that bear against the upright posts 2, 3, or 4 as the case may be. The 85 ends of the beams 13 do not extend as far beyond the flanges 14 as the beams 5 project beyond the flanges 6, except at the end aligning with a post 2, hence a space is left to receive the lower ends of posts 3^a between the 90 ends of the beams 13. It will also be noted that the upper faces of these beams are in a plane higher than the beams 5. The joists 7 and the beams 13 support the concrete floor slabs 8, details of which are shown in Figs. 95 6 and 7. These figures show especially the method of jointing the floors, Fig. 6 being a transverse section through the meeting portions of two slabs and Fig. 7 a longitudinal section.

It will be noted that the form of 100 joint shown in Fig. 7 comes on a cross beam, or some other support, such as a joist, while the joint shown in Fig. 6 may come at any point. In Fig. 7, 18 indicates the longitudinal reinforcing of the floor sections, with 105 a triangular metal mesh, and in Fig. 6 I show in cross section cold twisted bars 23 embedded in the slab above the mesh 18.

Fig. 6 shows the formation of joints at the sides of the slabs and Fig. 7 the joints 110 at the slab ends.

The joint in Fig. 6 is practically a tongue

and groove joint with a slightly beveled upper portion forming when the two sides are fitted together a small V-notch above the tongue and groove. This joint is fitted or 5 lined with three ply roofing composition and the notch filled in with hot sulfur or asphalt.

The slab ends are beveled their entire thickness so that at the ends a V-joint 10 is formed having a depth equal to the thickness of the floor. This is lined with roofing composition, also three ply, as at 17 and the same roofing composition, 17, is placed under the meeting ends and between the 15 floor slabs and the supporting beam 13. This joint is also filled in with hot sulfur or asphalt, or other equivalent waterproofing substance.

This construction makes a water tight 20 joint and the three ply roofing allows for expansion and contraction of the concrete slabs and beams.

The roof 24 is also of reinforced concrete 25 and is surmounted by a metal cornice 12, shown in detail in Fig. 5, and in plan view in Fig. 3. Wooden cross pieces 25 are embedded in the upper face of the concrete roofing and are locked in place by metal clamps 26, embedded in the concrete of the 30 roof and having their upper free end portions bent over the upper faces of the cross pieces 25, as shown in Figs. 3 and 4.

The roof 24 may also be of slabs similar 35 to the flooring and with similarly calked joints, especially where a waterproof formula is employed. In such case the wooden strips 25 may be omitted. But as shown in Fig. 4 I complete the roof by placing over the concrete surface, shown in Fig. 3 a four 40 ply tar felt roofing, the first ply being cemented to the concrete and the second nailed to the strips or cross pieces 25. The roof is then covered, about one half inch 45 deep, with gravel 27, bringing it level with the top of the galvanized edging or cornice 12.

This produces a watertight and fire resisting roof. Also one practically wind proof.

50 In Figs. 8, 9 and 10 I have illustrated details of the method of reinforcing the various beams and posts.

Referring more especially to Fig. 9 it will 55 be noted that these beams have inserted or embedded in them a series of angle irons 30 grouped so as to form four crosses, each consisting of four of the angle irons. The irons comprising each cross are connected at suitable intervals by rivets or bolts 31, and 60 the four crosses are tied together by metal bars 32. This construction is carried throughout the posts and beams and in addition thereto the beams are additionally reinforced at the arches as shown in Fig. 8.

Curved angle irons 32 being embedded in 65 the arches, braced by a cross piece 33, and tied to the irons 30 by tie rods 34.

In the end portions of the beams, projecting beyond the flanges 6 are transverse bars 35 which prevent crushing strains on 70 said end portions, and these bars extend a slight distance upwardly and downwardly into the upright posts 4. The beams are held securely in position by the bolted angle plates 15, anchored also to the beams by 75 embedded bolts, and by a bolt 37 extending through the lower portion of the flanges and the upright post, and having its head bearing against an anchored wear plate 38.

The three ply roofing composition 80 employed where two concrete members come in conjunction is indicated, in Fig. 8, at 36. As in the case of the floor joints this allows for expansion and contraction of the cement members.

85 The entire structure forms a rigid, durable, and fireproof building, and the concrete elements of which it is composed may be molded or formed at any desired place and be readily transported to and assembled in position.

Where wooden floors are desired over the 90 cement floors they may be embedded in the same manner as the roof strips. While I have shown the posts mounted on and bolted 95 to piers they may rest on a solid wall of any kind.

What I claim is:—

1. In a building, reinforced concrete upright members, reinforced concrete beams 100 resting on said upright members, concrete beams at right angles to those first mentioned and having reduced end portions resting on the first mentioned beams, joists carried by the first mentioned beams and 105 parallel with the second mentioned beams, and concrete floor sections resting on the second mentioned beams and the joists, said sections having V-shaped joints, a roofing composition fitted into said notches, and a 110 waterproof filling for said joints, the upper face of the filling being flush with the floor surface.

2. In a building of the kind described, the combination with concrete upright columns, concrete beams supported by said columns, and reinforced concrete floor sections, 115 said sections having a tongue and groove joint along their sides with a V-shaped groove formed above the tongue and joint, 120 and having beveled ends forming a deep V-shaped groove at the meeting ends of the sections, a roofing composition inserted between the various sections, and a waterproof filler positioned in the grooves, and 125 flush with the floor surface.

In testimony whereof I affix my signature.

JOSEPH P. PAULISSEN,
